Lindsay and twenty-five per cent to Ernest
Hix, both of Los Angeles, Calif.

Application May 29, 1933, Serial No. 673,515

7 Claims. (Cl. 179—6)

This invention relates to sound transmitting, recording and reproducing mechanisms generally.

The invention is primarily intended for use in connection with telephone systems. I am sufficiently acquainted with prior art devices and systems to appreciate that it is old in the art to provide means in a telephone circuit for recording sound whereby information may be subsequently conveyed to a person at one end of a telephone relative to the desire of other persons to converse with him telephonically during his absence. Broadly, my invention has to do with mechanisms wherein this same general function can be satisfactorily accomplished. In the prior art devices just above referred to, no means have been provided to permit of an exchange of audible sounds and signals at the respective ends of an intercommunicating telephone system; and it is in this respect broadly that my invention provides positively acting means of an automatic nature which will make known to a person at one end of the system the absence of a person at the other end of the line and then automatically convey to said person audible information of such nature as the subscriber actually intends to impart to him, and which then permits the person at said one end of the line to convey and record in the mechanism at the other end thereof any message which he desires to transmit. To my knowledge, these features of the invention have never been accomplished heretofore, and I wish, therefore, to lay particular emphasis upon the use in a telephone system of certain instrumentalities that will enable these desirable functions to be performed.

It is an important object of the invention to provide, in combination with a telephone system, sound recording mechanisms whose operations may be controlled in such manner that during the absence of a person at one end of the line or during a time when it is desired that he shall not be disturbed from other duties, he can, by accurately functioning means at his end, connect the apparatus in circuit with receiving and transmitting instruments of a telephone system whereby, in the absence of such person, one desiring to telephonically converse with him may be informed of his absence and advised that any desired message may be conveyed through the system for accurate recordation and subsequent reproduction thereof upon the return of said person.

It is a further object of the invention to pro-

vide in a telephone system sound recording means which will be positively acting and which will include respective recorders at one place in the system adapted to be connected in circuit with wound receiving and transmitting instruments of common construction; means for informing a person who desires to converse telephonically with another person of the latter's absence; means which functions after one has been thus informed, for automatically receiving from him the message which he wishes to convey; means for effecting the recordation of the message intended to be conveyed; means which will enable the user to readily have reproduced for him the message left in his absence; and means whereby the user may either permanently preserve the record of conversations received in his absence, or promptly effect destruction thereof, according as he shall desire.

Another object of the invention is directed to the provision in a system of the type herein referred to of means for successively and automatically effecting accurate recordation of all previously transmitted messages.

Another object of the invention is to provide mechanism wherein the recording medium may be used indefinitely without replacement.

It is a further purpose of my invention to accomplish all the foregoing objects with the use of standard telephone transmitting and receiving instruments and in such manner as to permit said instruments to be quickly connected in circuit with or disconnected from said instruments.

In the accompanying drawings,

Figure 1 is a diagrammatic illustration of my apparatus;

Fig. 15 is a structural detail of the invention.

It is to be borne in mind that the instruments, mechanisms and combinations thereof which mutually contribute to satisfy the objects herein recited are all designed and constructed so that the entire apparatus may be connected with any telephone instrument now in common use without requiring changes in the construction thereof and without, in fact, making any direct internal 15 electrical or mechanical connection whatsoever with the telephone instrument or requiring that any of the parts of the instrument be disturbed in any manner whatsoever during operation of the apparatus.

20 25 To this end, and in carrying the invention into practice, use is accordingly made of the telephone instruments 1 and 1a of conventional construction, the same adapted to be connected with the line 2 through parts of my apparatus 30 to be described presently.

Before describing the various electrical circuits employed, I deem it desirable to refer generally to the use in the system of somewhat similar recording mechanisms 3 and 4; switch 35 mechanisms 5 and 6; a transformer 7; a rectifier 8; a filter unit 9; relay mechanisms 10 to 20, inclusive; automatic control mechanisms 21 and 22; switches 23 and 24; and a source 25 of alternating current to the primary of the aforementioned transformer.

40 The mechanisms 3 and 4 are to a large extent very similar and, except for those changes in one which are not found in the other, it is believed that a description of one will suffice for the other. 45 With particular reference to Figures 4 to 8, inclusive, I show two reels 26 and 27, each of which is mounted on a supporting axis 28 and adapted to receive power through a co-acting worm train 29, the element 30 thereof being 50 fixedly secured to a shaft 31 adapted to be driven by a motor 32. As illustrated, the said shaft 31 is provided with a worm gear 33 in mesh with a large worm gear 34 on a rotary element 166, the latter forming a part of the aforementioned automatic 55 control mechanism 21 and to this extent the mechanism 3 is similar to said mechanism 4. As shown, the shaft 31 of the last said mechanism has its worm gear 33 in mesh with the worm gear 34 of the rotary element 235 of the aforementioned 60 automatic control mechanism 22. At this point I wish to call attention to the fact that it is intended, as will be hereinafter described, that the gear ratios of the respective elements 33 and 34 of the two mechanisms 3 and 4 shall be so calculated 65 that the element 34 of instrument 4 will revolve very much slower than, and preferably about one-tenth as fast as, the corresponding element 34 in the mechanism 3.

70 Each of the reels 26 and 27 is provided with a peripheral groove 36 adapted to accommodate the wound portions of any suitable well-known material 37 capable of being magnetized, such as steel wire. This wire is threaded through the recording head 38, and the latter is mounted for 75 vertical tilting movement and for horizontal

oscillatory motion in order that no material frictional resistance will be set up as the wire is paid from one reel and wound upon the other, and in order also that the wire may be uniformly wound upon said other reel. It is to be understood that the wire 37 is the sound recording medium, whose office is called into play when respective actuations are set up in the system, and that sound is adapted to be electro-magnetically recorded thereon and reproduced therefrom. At this point, it should be noted that during the recording of sound upon the wire 37, the movement of the latter is from left to right or from the reel 26 to the co-acting reel 27. A more complete description of the functional characteristics of the head 38 will be given hereinafter, and it will suffice at the moment to say that the frame 38a of the head, to which latter the body portion 38b is pivoted at 38c for vertical swinging movement, is dovetailed for accommodation in 10 a cross head or mounting 39. The said mounting is slotted at 40 for the accommodation of a guide pin 42, the slot 40 co-acting with said pin to allow for limited horizontal sliding movement of the head 38 in a direction transversely of the reel 25 onto which the wire is to be laid. The pin 42 connects with a rocker arm 43, which is pivoted at 44 to the support 39 and, as illustrated, one end of this rocker arm is formed with an elongated slot 45 which co-acts with the pin 46 of an 30 eccentric 47, the latter receiving its motion through a worm train 48 between the shaft 39 of said eccentric and the aforesaid shaft 31.

Each of the reels 26 and 27 has a hub 50 which partly projects into a thrust bearing 51 on the 35 axle 28, as shown to advantage in Figure 5. This bearing comprises mating elements 52 and 53 between which anti-friction bodies 54 are interposed. Fixed to the axle 28 is a collar 55 against which one end of a coil spring 56 bears, the opposite end of said spring engaging against one side of the element 52 of said thrust bearing. Secured to the shaft 28 is a female member 57 in which a portion of the hub 50 is received, and same is provided with a clutch or braking element in the 40 form of a flat disk 58 against one face of which the inner flat face of the wall 59 of said reel engages, the tendency of the spring 56 serving to yieldingly advance the reel against the disk 58. Within the reel is mounted a spiral spring 59a, 50 one end of which is secured at 60 to the reel and the other to the female member 57, as shown at 61.

On the shaft 28 is a disk 62 having a lateral pin 63 which projects into an arcuate slot 64 of 55 a disk 65, the latter pinned at 66 to said shaft. The disk 65 has secured thereto the element 67 of the worm train 29. The respective reels 26 and 27 of the two mechanisms 3 and 4 are mechanically similar with respect to the structural 60 parts last above referred to. It follows, on reference to either of the mechanisms 3 or 4, that the slots 64 in the disks 65 are so positioned relative to the pins 63 and relative to each other that when motion is set up in the shaft 31, each disk 65 will rotate independently of the adjacent disk 66 and for an interval of time represented by the length of its slot or until one end of the slot engages its coacting pin 63, at which time motion will be imparted to the disk 62, thence to the 70 respective reel. The springs 59a of the respective reels 26 and 27 mutually co-act to maintain a uniform tension on the wire 37, thus assuring an even uninterrupted movement of the wire through the co-acting recording head 38.

It remains to be stated with respect to these mechanisms 3 and 4 that the reels 26 and 27 of the mechanism 4 are of a greater capacity at their peripheral portions than the reels 26 and 27 of the mechanism 3, whereby more wire can be handled and accommodated thereby than is intended to be accommodated by the corresponding reels of said mechanism 3.

Referring specially to Figure 2, the primary winding 113 of the transformer 7 is adapted to be connected with any suitable source of alternating current supply. This transformer includes secondary windings 131 and 132, the latter designed to supply alternating current to various ones of the circuits employed, the purpose of which said circuits I will explain presently. The other secondary winding 131 connects the copper-oxide rectifier 8 through the conductors 187, 188 and 189, which said rectifier is connected with a filter unit including the choke coils 193 and 194 and condensers 196, 197 and 198 arranged in the customary manner as shown. This filter unit is employed for the purpose of transmitting the pulsating current received from the output of the rectifier 8 and for converting said current into a relatively uniform direct current, whereby to supply the conductors 199 and 200 with a relatively uniform direct current.

The switch 5 comprises a reciprocal bar 70 having switch blades 136, 71, 72, 107, 210 and 180 at spaced apart intervals, and same are adapted to respectively co-act with spaced apart contact devices 137, 207, 73, 206, 74, 211, 75 and 181. In Figure 2, the blades 107 and 210 are shown engaged with the contact devices 74 and 75 which are connected by the conductors 76 and 77 with the respective leads 78 and 79 of the telephone line 2. The condenser 80 and buzzer 81 are connected in series and across the leads 78 and 79. The reciprocal bar 70 is provided at one end with a longitudinal series of keeper notches 82 which are adapted to co-act with the reciprocal core of a solenoid 83, whereby to hold said bar in a position of selected adjustment. In the position of the bar 70 shown in Figure 2 of the drawings, the telephone instrument 1 is connected with the conductors 108 and 109 through the aforementioned switch blades 107 and 210, at which time the telephone instrument 1 can be used independently of any part of my special apparatus employed, excepting, of course, the buzzer 81.

When the bar 70 is shifted to its extreme position to the left, the switch blades 136, 107, 210 and 180 will engage with the contact devices 137, 206, 211 and 181, respectively, whereupon the instrument 3 is rendered operative primarily for recordation upon the wire 37 of the message which the party at the instrument 1 desires to transmit to any person who may call him in his absence.

It will be observed that the bar 70 is provided with a lug 89, adapted, when the bar is moved to its extreme position to the left, to engage against the free end of a resilient contact device 89' to thereby disengage the latter from a co-acting contact device 90. Simultaneously with this operation, the contact device 91, which is operatively connected by the insulating bar 91' with the device 89', is moved away from the co-acting contact device 92, for a purpose to appear as the description proceeds.

I have now described two adjustments of the switch 5, one of which is to a position at the extreme left and the other to an intermediate

position, and it will be also observed that said switch may be adjusted to a third or an extreme position to the right, at which time the switch blades 71 and 72 engage with contact devices 73 and 207 to establish connection between my automatic mechanism and the telephone line 2.

The switch 6 includes a reciprocal bar 6a of insulating material, and same is very similar in construction to the switch 5, and is provided with spaced apart blades 93, 151, 94, 95, 96, 97, 98 and 99, which respectively co-act with contact devices 100, 150, 214, 215, 216, 217, 218 and 219. This switch is shown in a position to bring the blade 151 into engagement with the contact device 150. One end of the switch is provided with a longitudinal series of keeper notches 220 adapted to co-act with the core of the solenoid 221 to lock the switch in respective positions of adjustment under conditions to appear presently. When the switch 6 is moved to its extreme position to the left, the blades 96, 97, and 98 engage with the respective contact devices 216, 217 and 218 and when said switch is moved to a position at the extreme right, the blades 93, 94, 95 and 99 are engaged with the contact devices 100, 214, 215 and 219. It will be noted that the contact devices 214 and 216 connect with the contact device 214a of the relay bar 348 through the conductor 133; that the blade 94 of the bar 6a connects with the contact device 94a of said bar 348 through the conductor 371; that the contact devices 215 and 217 connect with the contact device 215a of said bar 348 through the conductor 138, and that the blade 95 connects with the contact device 95a of said bar 348 through the conductor 319. During either of these extreme positions of the switch, it follows that the blade 151 is disengaged from its co-acting contact device 150.

The relay 10 includes a pivoted armature 139 which co-acts with electro-magnets 134 and 84, and same functions to impart sliding movement to the bar 85 of said relay, and, as illustrated, said bar is provided with a plurality of spaced apart non-conductor lugs 86 adapted to co-act with co-incident resilient contact devices 141, 143, 145 and 147, so that, when the armature is drawn toward the electro-magnets 134 and 84, the just mentioned contact devices will be moved into engagement with co-acting contact devices 142, 144, 146 and 148, respectively. On the bar 85 is a keeper 87 adapted to co-act with a normally retracted armature 88, the latter co-acting with an electro-magnet 204 so that when the latter is energized, said armature will be moved into latching engagement with said keeper 87.

The relay 13 has a longitudinally movable bar 222 of insulating material, the same being normally urged to the position shown in Figure 2 by virtue of a resilient contact device 223, the latter adapted to co-act with a contact device 224 when the bar is moved in one direction. The bar 222 carries contact devices 225 and 226, which are normally engaged with contact devices 227 and 228, and, as illustrated, said bar is provided with a lug 229 which rests against a contact device 230. When the electromagnet 232 is energized, the device 226 is disengaged from said device 228 and presented against a contact device 234; and the contact device 225, at the same time, moves away from the device 227 and is presented against the contact device 235. Also at this time the contact device 230 is acted upon by the lug 229 and advanced against the device 231. During this movement of the bar 222, the

contact device 223 will be advanced against the co-acting device 224. The bar 222 is provided with a keeper member 236, which under certain conditions to be hereinafter described, is adapted 5 to co-act with a normally retracted latching armature 237, the latter in turn being co-operable with an electro-magnet 238.

The relay 20 employs a longitudinally movable bar 239, which is normally urged to the position 10 shown in Figure 2 by the action of a resilient contact device 240, the latter adapted to co-act with a contact device 241. The bar 239 carries contact devices 242, 243 and 244, the device 244 co-acting with contact devices 157 and 245. The 15 device 243 is adapted to co-act with contact devices 161 and 246, and the contact device 242 is adapted to co-act with the contact device 247. The bar 239 is adapted to be urged in an opposite direction by a co-acting electro-magnet 248 20 and in line with the core of the magnet the bar is provided with armature arm 249. Under certain conditions, the said bar 239 is adapted to be locked against returning to normal position by an organization including a magnet 172, a co-acting 25 latching armature 173 and a keeper member 174, the latter carried by said bar.

The automatic control mechanism 21 includes the device 250 of insulating material, the same supported by a pivoted armature 176. Carried 30 by the armature 176 is a latch member 177, the latter being co-operable with the cam 167 to tilt the device 250 in the direction of the magnet 175 when the disk 166 is rotated counter-clockwise. The electro-magnetic coil 175 is of such 35 strength that, when energized, same will pull on the armature 176 with sufficient force to hold the armature after the latter is drawn down by the action of the cam 167 in the manner aforeslated. The device 250 carries yieldable contact devices 40 154 and 164, which normally engage the respective contact devices 153 and 165. It follows that when the cam 167 engages the device 177 during counter-clockwise rotation of the disk 166, the yieldable contact devices 154 and 164 will be 45 moved away from said contact devices 153 and 165, respectively. The cam 167 normally rests against the stop 168 positioned adjacent to the contact device 169 so as to hold the latter separated from the device 170, as shown in Figure 50 2. Because of the arrangement described, it follows that the device 169 will yieldingly move into engagement with the contact device 170 the moment the disk 166 starts to rotate in a clockwise direction.

55 The operative driving connection between the disk 166 and the shaft 31 is such as to effect a clockwise movement of the disk or a recording movement from left to right of the wire 37 until cam 167 is brought against the stop 251, at 60 which time substantially all of the wire 37 will be paid off of the reel 26 and wound upon the reel 27. As the cam 167 approaches the stop 251, it engages the resilient contact device 252 and forces same into engagement with the 65 silent contact device 253, which latter is operatively connected by the insulating material 253a to the resilient contact device 254, thus resulting in movement of the latter into engagement with the contact device 255.

70 The automatic control mechanism 22 shown in Figure 9 includes a bifurcated member 256 journaled on the shaft 275, and between the side arms of which the disk 235 is interposed. Said disk is carried by said shaft, and as illustrated, 75 the member 256 carries a yieldable friction shoe

257 which bears against the smooth peripheral surface of said disk. I provide a contact member 258 which rests against a stop 276, and same is adapted to co-act with a resilient contact device 259, the latter being operatively connected 5 by an insulating bar 259a to a yieldable contact device 260 so as to cause said devices 259 and 260 to move together. A resilient contact device 261 is provided with a free end 261a positioned to engage said member 256, the latter 10 normally tending to move with the disk 235, and when said disk is rotated in a clockwise direction. The member 256 thus functions to force the contact device 261 into engagement with the contact device 260 and because of the connection 15 between said contact devices 260 and 259, the latter will be forced against the contact device 258, at which time all of the four last mentioned contact devices will be simultaneously held in engagement in the relative order referred to, and 20 further movement thereof will be obstructed by the stop 276, and the member 256 will be restrained against further clockwise movement by the contact member 261. A cam 262 is rigidly secured to the rim of the disk 235, and same is 25 adapted to co-act with the portion 267 of a resilient contact device 266 when the cam is in the position illustrated in Figure 9. When the cam 262 is moved away from the contact device 263, the latter will automatically spring into engagement with the contact device 264. A stop 30 265 is provided to limit the movement of resilient contact device 266, which latter normally engages contact device 267 and is operatively connected by a bar 277 of insulating material to 35 contact device 269, the latter adapted to co-act with the contact device 268. The contact device 269 is provided with a free end portion 269a for engagement with the cam 262 when a clockwise rotation of the disk 235 brings the cam against 40 said contact member 269, at which time the latter will move into engagement with the contact device 268, and simultaneously therewith, the contact device 266 will move away from contact device 267 and into engagement with the stop 45 265. Because of the operation of the parts just described, it manifestly follows that the cam 262 will be held against further clockwise rotation. The mechanism 22 also includes an electro-magnet 270 and a co-acting pivoted armature 271, 50 the latter operatively connected to a reciprocal dog 272 so as to move said dog into a keeper notch 273 in said member 256, when the electro-magnet 270 is energized.

Each of the mechanisms 3 and 4 is preferably 55 mounted on a platform 278 and, as shown, a portion of the platform for the mechanism 4 is provided with an offset extension 279 having a slot 280 through which the cam 262 is adapted to pass as the disk 235 revolves. The offset portion 279 60 of the platform of the mechanism 3 is provided with a similar slot 281 which accommodates the movement of the cam 167 during rotation of the disk 166.

I have now described the essential mechanical 65 features of certain of the parts employed, and shall, therefore, proceed to describe the functional characteristics thereof in the various actuating and controlling circuits of the system. In the position of certain of the parts, it is to be noted that, for the purpose of clarity, the telephone instrument is so illustrated in the system that same may be used for normal service independent of the special parts of my apparatus.

Referring especially to the first three figures 75

of the drawings, it will be appreciated that by placing the bar 70 of the switch 5 in the extreme position to the left, the system is rendered operative for recording of a message which a person at the instrument 1 intends shall be automatically transmitted to a person desiring to telephonically communicate with him. This message to be recorded is spoken into the customary transmitter of the instrument 1, and with the switch 5 adjusted to the position just mentioned, current will flow through the secondary winding 132 of the transformer 7, conductor 133, electro-magnet 134, conductor 135, switch blade 136 of said switch 5, contact 137, thence through conductor 138 and back to said secondary winding 132. This circuit carries an alternating current which is induced in winding 132 from the primary winding 113 of the transformer 7, so as to energize electro-magnet 134 to thereby draw the armature 139 and bar 85 of the relay 10 into position to cause the lugs 86 of the said bar to advance the contact device 141 against the contact device 142 and to effect a like adjustment of the contact devices 143 and 144, contact devices 145 and 146, and contact devices 147 and 148. When the devices 143 and 144 are in the aforesated position of closed adjustment, the current flow is as follows:

From the secondary winding 132 of the transformer 7, the current flows through conductor 133, contact devices 143 and 144, conductor 149, contact device 150 of switch 6, switch blade 151, conductor 152, contact device 153 of the automatic control mechanism 21, contact 154, conductor 155, contact device 244, contact device 157, conductor 158, motor of the mechanism 3, conductor 160, contact device 161, contact device 162, conductor 163, contact device 164, contact device 165, conductor 138 then back to the secondary winding 132. This circuit carries alternating current to the motor so that power will be transferred to the disk 166 to move said disk in a clockwise direction, it being borne in mind that when recording the movement of the wire 45 is from left to right. When the disk 166 is thus rotated, the cam 167 thereof leaves the stop 168, whereupon the spring blade 169 is released and automatically springs into engagement with the blade 170. Current now passes through the conductor 152 which is in one side of a previously described alternating current circuit, through contact device 169, contact device 170, conductor 171, electro-magnet 172, thence to conductor 138 which is in the other side of the previously described alternating current circuit. This energizes the electro-magnet 172, so as to draw the latching armature 173 against the keeper arm 174 for a purpose to be hereinafter described. Inasmuch as the electro-magnetic coil 175 is connected across the opposite side of said previously described alternating current circuit by the conductors 138 and 152, it follows that same will also be energized.

It will be further observed that when the switch 5 is placed in the position last above mentioned, current flows from the secondary winding 132 through conductor 133, electro-magnet 178, conductor 179, switch blade 180, contact 181, conductor 138, and back to the secondary winding 132, at which time alternating current energizes the electro-magnet 178 to thereby draw the arm 182 into position to cause a closing of the contact devices 183 and 184 and a corresponding closing of the contact devices 185 and 186. When this is accomplished, direct current will be

available for operation of the telephone instrument 1, and when supplied as aforesated to the conductor 200 same flows through the contact device 186, contact device 185, primary winding 201 of the induction coil 202, conductor 203, contact device 147, contact device 148, electro-magnet 204, through conductor 205, contact device 206 of said switch 5, switch blade 107, conductor 108, telephone instrument 1, conductor 109, switchblade 210, contact 211, conductor 212, contact device 183, contact device 184, thence to conductor 199, the latter leading to said source of direct current supply. This circuit is continuous through the telephone 1 and the primary winding 201 of the induction coil 202, and is used to energize the electro-magnet 204 to draw the latching armature 88 into engaging position with arm 87 of the bar 85, thereby maintaining the contact devices 141-142; 143-144; 145-146 and 147 and 148 in positions of closed adjustment. The last-mentioned circuit remains uninterrupted until broken in the telephone instrument or until the switch bar 70 is moved to a position to cause the blades 107 and 210 thereof to be disengaged from the respective contact devices 206 and 211.

When the circuit discussed in the preceding paragraph is complete, and when a message is spoken into the telephone instrument 1, a modulated direct current will be inductively transmitted from the primary winding 201 of induction coil 202 to the secondary winding 282 of the same coil. This secondary winding 282 is in a circuit which is adapted to be closed when an actuation is set up in a circuit through which the current flows as follows:

From the secondary winding 132 alternating current passes through conductor 138, contact device 141, contact device 142, conductor 284a, coil 283, conductor 133, thence back to the secondary winding 132. This energizes the electro-magnet 283 and the latter draws the pivoted armature 284 into position to cause the lugs 285 on the bar 286 to effect engagement of the resilient contact device 287 with the contact device 288; resilient contact device 289 with contact device 290 and resilient contact device 291 with contact device 292. This causes a circuit through the secondary winding 282 of the induction coil 202 to be completed as follows:

From the secondary winding 202, the current flows through conductor 293, secondary winding 294 of the tone coil 295, contact device 225, contact device 227, conductor 296, contact device 289, contact device 290, conductor 297, recording and reproducing coil 298, conductor 299, contact device 292, contact device 291, conductor 300, contact device 228, contact device 226, conductor 301, thence back to the secondary winding 282. The secondary winding 184 of the induction coil 202 is now connected in a complete circuit with the recording and reproducing coil 298.

During the use of the previously described circuits for recording messages on the wire 37, the bar 302 of switch 23 is moved to a position so that lugs 303 thereof will force the resilient contact device 304 into engagement with the contact device 305 and in like manner cause the resilient contact device 306 to move into engagement with the contact device 307, at which time the flow of the current is as follows:

From conductor 200, which leads from the previously described source of alternating current, the current flows through contact devices 75

306 and 307, conductor 308, pre-magnetizing coil 333, conductor 309, contact device 247, contact device 242, conductor 310, contact device 305, contact device 304, thence to conductor 189, which leads to the previously described source of direct current. This circuit carries pre-magnetizing current for producing a uniform magnetic effect on the moving wire 37 to adapt same for receiving a change in magnetic properties thereof commensurate with magnetic impulses produced in coil 298 in accordance with the modulated current induced through induction coil 202.

In addition to having set forth the operation of the instrument, (Figure 4) when recording sound thereon, I have also set forth the operation of the instrument (Figure 9) as is necessary to uniformly move the wire 37 through the recording head 38 of the last said instrument and in a direction from left to right, so as to electro-magnetically record sound thereon.

I shall now describe the automatic operation of certain parts of the apparatus at a time when substantially all of the wire 37 has been moved as aforementioned in said direction from left to right in the instrument, Figure 9, and all wire substantially entirely wound upon the reel 27 of the mechanism 3. It will be apparent that the disk 165 of the mechanism 3 will have rotated clockwise to a position where the cam 167 engages the contact device 252 as shown in dotted lines (Figure 2), thus causing same to engage with and to move the contact device 253, which latter, in turn, causes the contact device 254 to engage with the contact device 255. Alternating current now flows from the conductor 152, which, as previously described, is at this time in one side of an alternating current circuit, thence through the contact devices 254 and 255, conductor 312, electro-magnet 248 of the relay mechanism 20, energizing the magnet 248 and thereby causing an opening of all contact devices in said mechanism 20, which are indicated as closed in said Figure 2, and a closing of all contact devices which are shown open in the said figure. Alternating current now flows to the conductor 138, which latter is in the other side of the previously described alternating current circuit. As previously set forth, the contact devices 169 and 170 are in engagement with each other at this time and said magnet 172 is energized. This magnet then draws the armature 173 into latching engagement with the arm 174 and causes the position of the parts of the relay mechanism 20 to be maintained as last stated during this period of time.

Current now flows from the contact 156 through contact device 245, conductor 313, motor 32, conductor 314, contact devices 246 and 162, conductor 163, contact devices 164 and 165, to the conductor 138, the latter leading to the source of alternating current supply. In consequence thereof, the motor is operated in a direction to cause the wire 37 to be unwound from the reel 27 and rewound onto the reel 26 of the mechanism 3.

When the contact devices of relay mechanism 20 are closed, to thus cause a flow of current for the re-winding of the wire 37, that is, for the winding of the wire on reel 26, it should be noted that the contact devices 241 and 242 are spaced apart and, therefore, the circuit through the pre-magnetizing coil 311 is always open during the re-winding operation. This insures that the record previously placed on the wire through the action of the recording coil 298 will not be altered

as a result of the person using the device failing to release the switch 23 during said re-winding operation. However, it is intended that switch 23 be released by the user of the apparatus when the re-winding operation is to proceed.

At this time, it is desirable to have a frequency note transmitted to the person using the telephone instrument 1 to audibly indicate to such person that the full capacity of the recording medium of the mechanism 3 has been used and that the bar 70 should be shifted into position to cause the switch blades 136, 107, 210 and 180 to be disengaged from the respective contact devices 137, 206, 211 and 82. In order to cause the sounding of this frequency note, at the time stated, I have provided the aforementioned automatic control mechanism 21 which functions to close the contact devices 252 and 253 to thereby cause alternating current to flow from conductor 138 through said contact devices 252 and 253, conductor 314, primary winding 315 of tone coil 295, thence to conductor 133. It has been previously described that the secondary winding 294 is at this time connected in a circuit which is continuous through the telephone and it follows that the alternating current now flowing through the primary winding 315 will produce an induced effect on the current now flowing through the secondary winding 294. This causes a note of the same frequency to be sounded at the instrument 1, whereupon the person using said instrument will be advised to shift the position of the bar 70, as is required at this instant, it having been stated that the motor 32 is now being supplied with alternating current in a manner to cause parts of the mechanism 3 to rotate the disk 166 in a counter-clockwise direction. As such rotation of the disk starts, the cam 167 quickly moves away from contact device 252, whereupon the latter and contact devices 253, 254 and 255 return to their normal positions. This causes the breaking of the circuit which supplied the primary winding 315 of the tone transformer with alternating current and consequently causes the sounding of the tone to cease. The returning of the last mentioned contact devices to their normal positions breaks the circuit through the electro-magnet 248 of relay mechanism 20. However, for the present, the previously described co-action of the electro-magnet 172, latching armature 173 and arm 174 prevents the relay bar 239 from returning to normal position.

It is important that the switch 5 be maintained with its bar 70 in the central position during the operation of re-winding the wire 37, and this is automatically made possible by a novel arrangement of co-operating parts which will now be described. When the relay mechanism 20 is in the position last referred to, at which time the co-acting contact members thereof are closed for the re-winding operation, it will be noted that contact devices 240 and 241 will be closed, and the electro-magnet 315 energized by an alternating current which flows from conductor 133, through electro-magnet 315, conductor 316, contact devices 241 and 240, thence through conductor 138 to the source of alternating current. When thus energized, electro-magnet 315 draws pivoted armature 317 and thereby transmits motion to bar 318 so that the lugs 319 thereon will close the contact devices 322 and 323. This compels operation of the solenoid 83 of switch mechanism 5 by a current which flows from the secondary 132 of the transformer 75

7, though conductor 133, contact devices 323 and 322, conductor 314, contact devices 91 and 92, conductor 325, solenoid 83, conductor 324, contact devices 320 and 321, to conductor 138, back to the said secondary 132. The action of the solenoid 83 at this time is such as to force the plunger thereof into the central one of the keeper notches of the bar 70 to hold the latter in the aforesigned central position during said re-winding operation. During a portion of the counter-clockwise rotation of disk 166, the cam 167 contacts with latch 177 to shift device 250 to a position to open the contact devices 165 and 164 and 153 and 154, and this causes both of the circuits through the motor to be broken. However, the force of momentum of parts of the apparatus which are in motion carry disk 166 further in a counter-clockwise direction until the cam 167 engages the contact device 169 so as to move same into the normal position shown in Figure 2, whereupon the circuit through the electro-magnet 172 is opened. This allows the latching armature 173 to be retracted from the arm 174, to thereby free the bar 239 and allow the parts of the relay mechanism 20 to return to their normal positions.

At this stage in the operation of my mechanism, the motor is stopped and all parts of the mechanism are returned to their normal positions. It is intended that there now be a record in the form of a variable magnetic structure of the wire which is capable of causing a modulated current in the winding of the recording and reproducing coil 298 when the wire is moved through the recording head 38 in a direction from left to right, and that the modulated current thus produced will cause to be produced at the telephone instrument 1 the audible message which was previously spoken in said instrument. In case the user of the apparatus desires to listen to the message, the switch bar 70 is moved to the extreme left position. When this is done, the parts occupy the positions previously described, except for the fact that the pre-magnetizing circuit is now inoperative, and except also for the fact that the modulated current is induced through the induction coil 202 in an opposite direction to the movement when recording. As the wire travels from the reel 26 to the reel 27, the message previously spoken into the telephone instrument 1 will be rendered audible at said instrument 1, and following the message the tone will be sounded just as before. Upon hearing the tone, and if the user of the apparatus is satisfied with the message thus recorded, the bar 70 is adjusted to the central position, at which time the parts will be automatically restored to their normal or starting positions.

In case the message just listened to is not satisfactory, or there exists some reason to erase the whole or any portion thereof, this can be accomplished by putting the switch bar 70 to the extreme left position and holding the contact members of switch mechanism 24 closed during the time that the portion of the record which it is desired to erase passes through the recording head 38. The contact devices of said switch mechanism 24 may be held in their positions of closed adjustment by manually moving bar 326 so as to cause its lugs 327 to urge the resilient contact device 328 into engagement with contact device 329 and to urge the resilient contact device 330 into engagement with contact device 331, whereupon direct current flows from the previously described source of direct current through conductor 199,

contact devices 328 and 329, conductor 332, erasing coil 311, conductor 334, contact devices 330 and 331, conductor 200 to the source of direct current. The direct current flowing through the winding of erasing coil 311 produces a strong uniform magnetic field and the magnetic structure of the portion of the wire which passes through this field is made uniform by the action of this field, thereby removing the record of the message on that portion of the wire being acted upon. 10 Following this erasing operation, and when the wire has been entirely unwound from the reel 26, the tone will be sounded as before, at which time the user of the instrument 1 releases the switch mechanism 24 and moves the switch bar 70 of 15 the switch mechanism 5 to return the latter to its central position of adjustment. All parts of the apparatus will now automatically return to their normal or starting positions.

I shall now describe the operation of my apparatus when the same is connected with the telephone line 2. Let us assume that there is now a record of a previously recorded message on the wire 37 of mechanism 3. My special apparatus is rendered automatically operative with respect to 25 the telephone line 2 by placing switch bar 70 of switch mechanism 5 in the extreme position to the right. Assuming that this has been done, it will be observed that the normal direct current of the telephone line will tend to flow from lead 30 78 of the telephone line 2 through contact device 73, switch blade 72, conductor 212, condenser 335, electro-magnet 336, conductor 205, switch blade 71, contact device 207 and back to lead 79 of the telephone line 2. Although there is, normally, 35 this tendency for a flow of direct current, an actual flow of direct current is blocked by the action of the condenser 335 and for this reason the electro-magnet 336 does not become energized by just the normal direct current of the telephone 40 line.

When a person at the instrument 1a endeavors to communicate with someone at the telephone instrument 1, an alternating current intended to produce the ringing signal is sent through the 45 line 2 and flows through the same parts of my apparatus as does the direct current just mentioned. The condenser 335 permits the flow of this alternating current and the electro-magnet 336 is energized by said alternating current, whereupon 50 the pivoted armature 337 is drawn by the electro-magnet 336 so as to press resilient contact device 338 into engagement with contact device 339. This causes alternating current to flow from conductor 133 through electro-magnet 84, conductor 55 340, contact devices 338 and 339 to conductor 138. As previously described, when coil 84 is thus energized, relay mechanism 10 operates to close all contacts therein. It follows from the preceding description of the manner in which certain parts 60 of my apparatus operate when the contacts in relay mechanism 10 are closed that the record of the message previously recorded on the wire 37 will now be reproduced in the recording and reproducing coil 298, conducted by parts of my 65 apparatus to induction coil 202, transmitted by the latter and conducted by parts of my apparatus to the line 2. The previously recorded message will at this time be automatically switched over this line 2 to the telephone instrument 1a 70 of the person at the last named instrument.

The contact devices of the relay mechanism 10 are maintained closed during the automatic transmission of the message to the person at said instrument 1a. In order to accomplish this, I em- 75

ploy a dash pot 341, which is operatively connected to the armature 11 so as to cause the latter to hold contact device 338 in engagement with contact device 339 for a period of about one second 5 after the flowing of alternating current for the ringing signal. This is done because the direct current which is normally on the telephone line is cut off when the alternating current is used for the ringing signal, and it is desired to use the 10 normal direct current of the telephone line to energize electro-magnet 204. The holding of contact device 338 in engagement with contact device 339 for a short interval of time enables the direct current of the telephone line to flow 15 through parts of the apparatus as will be understood from the description of the recording operation previously set forth, and in so doing this direct current energizes electro-magnet 204 and draws the latching armature 88 so as to hold the 20 latter in engagement with the arm 87, whereupon all the contact devices of relay mechanism 10 will be maintained closed.

It is important to note that we are now considering the operation of the apparatus at a time 25 when the switch mechanism 5 is in a position to close the respective contact devices 89 and 90 and 91 and 92.

It is intended that the message to be automatically transmitted to the caller will be of a 30 nature to advise him of the fact that upon his hearing the tone any message which he desires to transmit will be conveyed through the system for recordation at the telephone instrument 1. Following the automatic transmission of such 35 message, the cam 167 will strike contact device 252 (Figure 4) and, as previously described, a circuit will be closed for a short interval of time while the motor is being reversed, which circuit carries an alternating current for use in producing 40 the frequency note or tone. Part of this same alternating current which is caused to flow at this time will be utilized to energize electro-magnet 232, the current flowing from conductor 133 through electro-magnet 232, conductor 342, 45 contact devices 89 and 90, thence to conductor 314. The closing of the contact devices 252 and 253 is for such a short interval that electro-magnet 232 is only energized for a corresponding interval. However, it is desired to have electro- 50 magnet 232 energized for a longer period of time and for this reason it will be noted that when same is energized the operation of the relay mechanism 13, as previously described, will cause all contact devices in said relay mechanism which 55 are shown closed in Figure 2 to be immediately opened and all other co-acting contact devices of said relay to be closed and the relay mechanism placed in a latched condition. This latching 60 of the relay is effected by alternating current flowing from conductor 133 through contact devices 145 and 146, conductor 243, electro-magnet 238, contact devices 223 and 224, conductor 344, contact devices 267 and 266 to conductor 138, thus energizing the electro-magnet 65 238 so as to draw the armature 237 into latching engagement with the arm 236. This latched condition of the parts remains effective until contact is broken between contact devices 145 and 146 or between contact devices 266 and 267 as 70 will be described later.

It will be observed that alternating current is now flowing from conductor 133 through contact devices 230 and 231, conductor 345, electro-magnet 346 to conductor 138, thus energizing 75 the electro-magnet 346 to draw armature 347

of the relay bar 348 and thereby move the latter so that the lugs 349 thereof will function to bring all of the contact devices of said relay to relatively closed positions. Alternating current will now flow from conductor 133 through contact devices 350 and 351, conductor 352, motor 32 of mechanism 4, conductor 353, contact devices 354 and 355, thence to conductor 138. The motor 32 will now operate in a direction to cause the wire 37 of mechanism 4 to be paid off reel 26 10 and wound on reel 27. At this time the current which is induced in the secondary winding 282 of the induction coil 202 will flow through conductor 293, secondary winding 294 of tone coil 295, contact devices 225 and 235, conductor 356, 15 contact devices 357 and 358, conductor 359, secondary winding 360 of tone coil 361, conductor 362, recording and reproducing coil 363, conductor 364, contact devices 365, and 366, conductor 367, contact devices 234 and 226, conductor 20 301 to the secondary winding 282 of the induction coil 202.

I shall now discuss the operation of parts of my apparatus when the motor 32 of the mechanism 4 is supplied with alternating current in 25 a manner to cause it to rotate the disk 235 in a clockwise direction. As previously described during a counterclockwise rotation of the disk 235 and as a result of the pressure exerted by the member 256, contact will be made between contact devices 261 and 260 and between contact devices 259 and 258. The closing of the latter contact devices causes a direct current to flow from the previously described source of direct current through conductor 199, contact devices 288 and 287, conductor 368, pre-magnetizing coil 415, conductor 370, contact devices 259 and 258, conductor 200 of the previously described source of direct current. Pre-magnetizing coil 415 is adapted to produce a magnetic field for magnetizing wire 31 uniformly as it travels from left to right. This pre-magnetizing operation in mechanism 4 is for a similar purpose as described with respect to the operation of mechanism 3.

I have now described the circuits that are 45 closed when parts of my apparatus are operated for automatically recording any message spoken into the transmitter of the telephone instrument 1a. It will now be observed that when the person calling hangs up his receiver the circuit in the 50 telephone line 2 will be broken and consequently the electro-magnet 204, which is in this circuit, will cease to be energized, whereupon the latching armature 88 will automatically return to normal position, so as to release arm 87, at which 55 time relay mechanism 10 will return to normal position and cause all contact devices therein to be opened. The opening of contact devices 145 and 146 in relay mechanism 10 will cause the opening of the circuit to electro-magnet 238, 60 whereupon latching armature 237 will spring out of engagement with arm 236 to thereby enable relay mechanism 13 to return to a normal position. This causes an opening of the contact devices 230 and 231 and a breaking of the circuit to electro-magnet 346, whereupon relay mechanism 16 will return to its normal position. Returning of relay mechanism 16 to said normal position causes the breaking of contact devices 350 and 351 and the devices 355 and 354 and the 65 breaking of the circuit to the motor, so as to stop the latter.

Now, let us consider that the user of the telephone instrument 1 has returned and wishes to hear the message which was recorded in his ab- 70 75

sence. The user merely moves switch bar 6a of the switch mechanism 6 to the position to the extreme right, which is the position for which said switch is set when it is desired to have the wire 37 re-wound on reel 26 and disk 235 rotated counter-clockwise until cam 262 has moved into engagement with contact device 263. When the switch bar 6a is placed in this extreme position to the right, alternating current will flow from conductor 133, contact device 214 of switch mechanism 6, switch blade 94, conductor 371, motor 32 in a manner to cause re-winding of the wire 37 on reel 26, thence through conductor 372; contact devices 263 and 264, through conductor 373, thence through electro-magnet 398 of relay mechanism 18, conductor 319, switch blade 95 of switch mechanism 6, contact device 215 and to the conductor 138.

This alternating current by flowing through electro-magnet 398 energizes the same to draw pivoted armature 374 and in turn impart motion to the bar 375, so that the lugs 376 will cause the resilient contact device 377 to be brought into engagement with the contact device 378 and the resilient contact device 379 into engagement with contact device 380. The closing of the contacts of said relay mechanism 18, as just described, causes alternating current to flow from conductor 133 through contact devices 378 and 377, conductor 381, electro-magnet 382, conductor 383, electro-magnet 384, conductor 385, contact devices 379 and 380 to conductor 138. Because of the flow of this alternating current through electro-magnet 382, the latter draws pivoted armature 386, which in turn imparts motion to bar 387, so as to cause the lugs 392 thereof to move resilient contact devices 388 and 390 into engagement with contact devices 389 and 391, respectively. The engaging of these last mentioned contact devices causes alternating current to flow from conductor 133 through contact devices 389 and 388, conductor 393, solenoid 221, conductor 394, contact devices 395 and 396, conductor 397, contact devices 390 and 391 to conductor 138. The flow of alternating current as just described through solenoid 221 causes the plunger of the latter to engage the keeper notch 220 at the left of the bar 6a and thereby hold said bar against movement while alternating current is flowing through the motor 32 and during the operation of rewinding the wire 37 on the reel 26 of the mechanism 4.

It should be understood that the switch bar 10 of switch mechanism 5 is placed in its normal position and locked therein during the rewinding operation of said mechanism 4. In order that this locking may be automatically accomplished, I provide the bar 6a of the mechanism 6 with a switch blade 93 adapted to co-act with the contact device 100. This enables alternating current to flow from conductor 133 through electro-magnet 400 of relay mechanism 17 through conductor 401, through contact device 100, through switch blade 93 to conductor 138. This alternating current by flowing through electro-magnet 400 causes the latter to draw pivoted armature 402, to thereby cause a closing of all co-acting contact devices in relay mechanism 17, whereupon alternating current flows through a previously described circuit to operate solenoid 325 and thus lock the switch mechanism 5 in said normal position.

As substantially all of the wire 37 becomes re-wound upon reel 26, the cam 262 on disk 235 engages with contact devices 263 to move the latter

out of engagement with contact device 264 whereupon the circuit through the electro-magnet 398 is broken, which enables the relay mechanism 18 to return to the normal position and causes the circuit through the electro-magnet 382 to be broken. This also causes an automatic opening of the contact devices in relay mechanism 17, whereby the circuit through the solenoid 221 will be broken. The plunger of the solenoid 221 will at this time return to normal position, allowing the switch bar 6a of switch mechanism 6 to be automatically returned to the central position by the action of the springs 399. This breaks the flow of current to the motor and causes the same to stop. It also causes switch blade 93 to move away from contact device 100 so as to break the circuit through the electro-magnet 400, whereupon the contact devices in switch mechanism 17 are opened and the circuit to solenoid 83 correspondingly opened so as to free the bar 70 from the core of said solenoid.

During the previously described counter-clockwise rotation of disk 235, the member 256 will move with said disk to an extent equal to the full counter-clockwise rotation of said disk.

I shall now explain the operation which is set up in the mechanism 4 during the reproduction of sound from the record wire 37 of said instrument. In order that the sound may be reproduced at the receiver of the instrument 1, the switch bar 70 of the switch mechanism 5 is adjusted to its extreme position at the left and the switch bar 6a of switch mechanism 6 moved to the extreme position to the left. Alternating current will flow from conductor 133 through contact device 216 of switch mechanism 6, switch blade 96, conductor 403, electro-magnet 404, conductor 352, motor 32, conductor 353, switch blade 97 of switch mechanism 6, contact device 217 to conductor 138. As previously described, the flowing of alternating current through the motor 32 of mechanism 4 causes said mechanism 4 to move the wire 37 through the recording and reproducing coil 363 in a direction from left to right. This same current that drives the motor 32 of mechanism 4 also energizes electro-magnet 404 to draw its armature, whereby to operate the relay mechanism 18 in a manner similarly described with respect to the action of the coil 398. This causes the contact devices in relay mechanism 18 to be closed and it follows from the previous description that when these devices are closed, the electro-magnet 384 of switch 24 will be energized; all contact devices will be closed in relay mechanism 15; and the switch bar 6a of the switch mechanism 6 will be locked by the action of the solenoid 221 in the extreme position to the left.

The wire 37 will now pass through the recording and reproducing coil 363 and the modulated magnetic structure thereof produced by any previously recorded message will cause a modulated current to flow through the winding of said coil 363 and through previously described parts of my apparatus, including the secondary winding 282 of the induction coil 202. This fluctuating current will be inductively transmitted through the induction coil 202 to produce pulsating effect on the current flowing to the telephone instrument where the previously recorded message will be made audible to the user at the telephone instrument 1. When the end of the previously recorded message is reached, the member 273 will be carried by the disk 235 so as to cause said member to press the contact device 261 into engagement with the contact device 260, at which time and as pre-

viously described the contact devices 259 and 258 will be brought into engagement. This will cause a frequency note or tone to be sounded at the telephone instrument indicating the end of the record. This is due to the fact that alternating current is now flowing from the conductor 133 through the primary winding 371 of the tone transformer 361, through conductor 372, switch blade 98 of switch mechanism 6, thence through conductor 406, electro-magnet 407, conductor 408, contact devices 260 and 261 to conductor 138. It will be observed that this causes a flow of current through electro-magnet 407 which draws pivoted armature 409, allowing the resilient contact device 395 to disengage from contact device 396. This breaks the flow of alternating current through the solenoid 221 and causes the switch bar 6a of switch mechanism 6 to be released and automatically returned to the normal position, at which time the circuit to the motor is broken and the motor will stop. The returning of switch bar 6a to said normal position also terminates the sounding of the frequency note because the circuit producing the same is broken upon the return of said bar 6a to said normal position.

It is important to note, at this point in the description, that the parts of the automatic control mechanism 22 are in the same relative positions that they were at the time when the person making the first call which was recorded at the mechanism 4 hung up the receiver of the instrument 1a. Let us consider that the switch bar 70 of the switch mechanism 5 is placed to the extreme position to the right and that switch bar 6a of switch 6 is placed to the extreme position to the left. This will render my apparatus operative to automatically transmit the message by the use of mechanism 3 over the telephone line 2 and to automatically enable additional messages to be recorded by the mechanism 4 as same are taken into line 2 from said instrument 1a. One long message or a number of short messages may be recorded on the wire 37 of mechanism 4, depending upon the capacity of the reels 26 and 27, and when all of the wire is used, the cam 262 will have moved to a position where the contact device 269 will engage the contact device 268. At the same time, the arm 277 will have been moved to disengage the contact device 266 from the contact device 267. The breaking of the contact between the devices 266 and 267 breaks the circuit through electro-magnet 238 of the relay mechanism 13, whereupon the latching armature 337 is yieldingly disengaged from the arm 236, so as to allow the relay mechanism 13 to automatically return to its normal position. This compels disengagement of the contact device 230 from the device 231 so as to open the circuit to electro-magnet 346 of relay mechanism 16, the latter then returning to its normal position so as to open all of its co-acting contact devices, including those in the circuit to the motor 32, thus stopping said motor. The closing of contact between devices 269 and 268 produces an effect as though the party calling had hung up his receiver. This is accomplished by producing a short-circuit across the line through which the telephone direct current is flowing, at which time current flows from conductor 205 at one side of the circuit, carrying the direct current of telephone line, through contact device 269, contact device 268, thence to conductor 212, which latter is in the other side of the circuit carrying said direct current.

The apparatus can only be rendered operative for further use by placing the switch bar 6a of switch mechanism 6 in the position for the rewinding operation and then allowing mechanism 4 to pass through the full cycle of the rewinding operation as previously described.

At any time that it is desired to erase a message which has been previously recorded on the wire 37 of mechanism 4, the user of the telephone 1 places the switch mechanisms 6 and 5, respectively, in positions for the rewinding operation and at the same time manually depresses bar 326 of switch mechanism 24, to thereby close the co-acting contact devices 328—329 and 330—331. As previously described during the rewinding operation electro-magnet 384 is energized with alternating current. When so energized this electro-magnet draws pivoted armature 411 to thus impart motion to the latch 412 through the link 413, thereby causing the latch 412 to engage with 20 the keeper arm 414 of the bar 326. The switch mechanism 24 is now automatically locked and the contacts 328—329 and 330—331 secured in closed positions. This causes a circuit to be closed during the rewinding operation and supplies direct current to the erasing coil 369 so as to produce a magnetic effect on the wire 37 in a similar manner to that explained with respect to the use of the erasing coil 371 in mechanism 3. It has been previously described that the conductors carrying this direct current for the erasing operation are 334 and 332. The direct current will now flow from conductor 334 through contact device 219, switch blade 99 of switch mechanism 6, conductor 416, erasing coil 369 to 35 conductor 332. This direct current will energize electro-magnet 417 which is connected between conductors 416 and 332. When thus energized, electro-magnet 417 draws the pivoted armature 418 so that the contact device 419 will engage 40 with the contact device 420. Alternating current now flows from one of the energized alternating current leads to the motor 32, through contact devices 419 and 420, through conductor 421, electro-magnet 270, thence back to the other one of 45 the energized leads to said motor. When this electro-magnet 270 is energized as described, the reciprocal dog 272 engages with keeper notch 273 in member 256, whereupon member 256 is held in a fixed position while disk 35 rotates to a 50 starting position. The rewinding and erasing operation continues until cam 262 strikes contact device 263, whereupon the circuit to the motor is opened so as to stop the motor. The circuit through the electro-magnet 384 of switch mechanism 24 is opened and the contact devices in the switch mechanism 24 likewise opened. The circuit to solenoid 221 is opened and the switch bar 6a of switch mechanism 6 is returned to a central position and the respective parts of the apparatus are now restored to the conditions shown in Figures 2 and 3.

From the above description, it will be appreciated that I have provided positively acting means whereby when the respective mechanisms 3 and 4 are operatively connected in circuit with the telephone instrument 12, the said mechanisms will be successively thrown into operation automatically in order that sound previously recorded at the instrument 3 will be first rendered clearly audible at said instrument 1a, following which sound may be taken into the telephone line from the transmitter of the instrument 1a and accurately recorded by the mechanism 4 for subse- 75

quent reproduction at the receiver of the instrument 1. I have also provided means whereby the respective mechanisms 3 and 4 can be selectively controlled by the user of the instrument 1 in order that sound may be recorded at the mechanism 3 during use of the transmitter of said instrument 1, then reproduced at the receiver of said instrument, and finally reproduced at the receiver of the instrument 1a. It follows further that the mechanism 4 can be readily connected in circuit with the receiver of the instrument 1, so that sound previously recorded by the last named mechanism may be reproduced at the receiver of said instrument 1 whenever desired. The said mechanisms 3 and 4 are further designed and constructed so that a predetermined actuation of one thereof will effect conditions in the circuits employed whereby to automatically place the other said instrument in operation for a predetermined time, after which the various instrumentalities employed in said circuits will be returned to their former positions preparatory to the next operation thereof. I have further provided means for effectively reversing the direction of rotation of the reels of each of said mechanisms 3 and 4 so that the wire can be wound from any one reel of a particular mechanism to the other reel of the same mechanism, for any one of the purposes herein referred to, including the operation necessary to effect either a partial or an entire cancellation from the wire of any sound recordations contained thereon.

I claim as my invention:

1. A telephone circuit including co-operable pairs of transmitting and receiving instruments, sound recording mechanism including a pair of co-operable rotary reels, a driving motor for said reels, a circuit in which the motor is connected, a flexible metallic recording medium co-operable with the reels and adapted to be paid from one to the other thereof, an electrically controlled recording and reproducing head co-operable with the medium, switch means in the motor circuit for placing the recorder in circuit with a transmitting instrument at one place in the line of the telephone circuit and for operating the motor to move the wire to effect recordation of sound thereon as same is formed at said transmitting instrument and the medium drawn through said head, the switch means serving when adjusted to another position to operatively place the recorder in circuit with one of the receiving instruments at another place in said line and for acting upon the motor circuit to cause the motor to operate for a predetermined period of time so that as the medium is moved in the effective presence of the recording and reproducing head, sound will be reproduced at said receiving instrument, and means for automatically reversing the direction of movement of the reels after each sound reproducing operation thereof.

2. A telephone circuit including co-operable pairs of transmitting and receiving instruments, sound recording mechanism including a pair of co-operable rotary reels, a driving motor for said reels, a circuit in which the motor is connected, a flexible metallic recording medium co-operable with the reels and adapted to be paid from one to the other thereof, an electrically controlled recording and reproducing head co-operable with said medium, switch means in the motor circuit for placing the recorder in circuit with a transmitting instrument at one place in the line of the telephone circuit and for operating the motor to move the said medium to enable recordation

of sound upon the latter as same is formed at said transmitting instrument and the medium drawn through said head, the switch means serving when adjusted to another position to operatively place the recorder in the line of said circuit and to connect same with one of the receiving instruments at another place in said line and for operating the motor for a predetermined period of time so that as the medium is moved in the effective presence of the recording and reproducing head, sound will be reproduced at said receiving instrument, means for automatically reversing the direction of movement of the reels after each sound reproducing operation thereof, and means for electro-magnetically acting upon said recording medium to erase therefrom any part or all of the sound recordation contained thereon.

3. In a telephone message receiving and transmitting apparatus, a telephone circuit including two inter-communicating subscriber substations each having a transmitting instrument and a receiving instrument; sound recording and reproducing mechanism having a magnet head and a record medium of magnetizable strip metal; means for mounting the record medium for movement linearly through said head; a motor; means controlled by the motor for moving the record medium; a circuit including a source of current supply; a circuit controller for including the motor in the circuit to move the record medium through said head; said controller including means operable during movement of the record medium to place said mechanism in circuit with the transmitting instrument at the called substation, or for placing said mechanism in circuit with the receiving instrument at the calling substation during movement of the record medium, whereby to enable sound from the called substation to be recorded by said mechanism, or be reproduced thereby for reception at the calling substation; and means by which the direction of movement of the record medium can be reversed to restore the latter to an original position for reproduction of a record on said medium.

4. In a telephone message receiving and transmitting apparatus, a telephone circuit including two inter-communicating subscriber substations each having a transmitting instrument and a receiving instrument; sound recording and reproducing mechanism having a magnet head and a record medium of magnetizable strip metal; means for mounting the record medium for movement linearly through said head; a motor; means controlled by the motor for moving the record medium; a circuit including a source of current supply; a circuit controller for including the motor in the circuit to move the record medium through said head; said controller including means operable during movement of the record medium to place said mechanism in circuit with the transmitting instrument at the called substation, or for placing said mechanism in circuit with the receiving instrument at the calling substation during movement of the record medium, whereby to enable sound from the called substation to be recorded by said mechanism, or be reproduced thereby for reception at the calling substation; means by which the direction of movement of the record medium can be reversed to restore the latter to an original position for reproduction of a record on said medium; and means for electro-magnetically erasing from said medium any part or all of a sound record therefrom.

5. In a telephone message receiving and transmitting apparatus, a telephone circuit including two inter-communicating subscriber substations each having a transmitting instrument and a receiving instrument; sound recording and reproducing mechanism, one for each substation and each having a magnet head and a record medium composed of magnetizable strip metal; motors by which the record mediums of the respective 5 mechanisms can be moved through the respective magnet heads; means for connecting one of said mechanisms with the receiving instrument at the calling substation and for supplying current to the respective motor to move the record medium of the mechanism through the magnet head thereof; means for connecting the other of said mechanisms with the transmitter at the calling substation and for supplying current to the other motor to move the other record medium through 10 its magnet head; and electro-magnetically controlled means at the called substation for erasing from either or both record mediums any part or all of a sound record therefrom.
6. In a telephone message receiving and transmitting apparatus, a telephone circuit including two inter-communicating subscriber substations each having a transmitting instrument and a receiving instrument; sound recording and reproducing mechanism one for each substation and each having a magnet head and a record medium composed of magnetizable strip metal; motors by which the record mediums of the respective mechanisms can be moved through the respective magnet heads; means for connecting one of said 15 mechanisms with the receiving instrument at the calling substation and for supplying current to the respective motor to move the record medium of the mechanism through the magnet head thereof; means for connecting the other of said mechanisms with the transmitter at the calling substation and for supplying current to the other motor to move the other record medium through its magnet head; means for connecting one of said mechanisms with the receiving instrument at the calling substation and for supplying current to the respective motor to move the record medium of the mechanism through the magnet head thereof; means for connecting the other of said mechanisms with the transmitter at the calling substation and for supplying current to the other motor to move the other record medium through its magnet head; means for connecting either one of said mechanisms with the receiving instrument at the called substation; means for connecting the first mentioned one of said mechanisms with the transmitting instrument at the called substation; and electro-magnetically controlled means at the called substation for erasing from either or both record mediums any part or all of sound records therefrom.

mechanisms with the transmitter at the calling substation and for supplying current to the other motor to move the other record medium through its magnet head; means for connecting either one of said mechanisms with the receiving instrument at the called substation; and means for connecting the first mentioned one of said mechanisms with the transmitting instrument at the called substation.

7. In a telephone message receiving and transmitting apparatus, a telephone circuit including two inter-communicating subscriber substations each having a transmitting instrument and a receiving instrument; sound recording and reproducing mechanism one for each substation and each having a magnet head and a record medium composed of magnetizable strip metal; motors by which the record mediums of the respective mechanisms can be moved through the respective magnet heads; means for connecting one of said mechanisms with the receiving instrument at the calling substation and for supplying current to the respective motor to move the record medium of the mechanism through the magnet head thereof; means for connecting the other of said mechanisms with the transmitter at the calling substation and for supplying current to the other motor to move the other record medium through its magnet head; means for connecting either one of said mechanisms with the receiving instrument at the calling substation and for supplying current to the respective motor to move the record medium of the mechanism through the magnet head thereof; means for connecting the other of said mechanisms with the transmitter at the calling substation and for supplying current to the other motor to move the other record medium through its magnet head; means for connecting either one of said mechanisms with the receiving instrument at the called substation; means for connecting the first mentioned one of said mechanisms with the transmitting instrument at the called substation; and electro-magnetically controlled means at the called substation for erasing from either or both record mediums any part or all of sound records therefrom.

JERRY B. FAIRBANKS.
